Primary Examiner — Patricia A Palasik(74) *Attorney, Agent, or Firm* — Hill & Schumacher(57) **CLAIM**

The ornamental design for a robotic joint, as shown and described.

DESCRIPTION

FIG. 1 is perspective view of the robotic joint showing our new design;

FIG. 2 is a front view thereof;

FIG. 3 is a right side view thereof;

FIG. 4 is a top view thereof;

FIG. 5 is a rear view thereof; and,

FIG. 6 is bottom view thereof.

The broken lines in the drawings depict unclaimed environmental subject matter.
